US00D919592S

(12) **United States Design Patent** (10) Patent No.: **US D919,592 S**
(45) Date of Patent: **** May 18, 2021**

(54) **WIRELESS AUDIO HEADSET**

- (71) Applicant: **Swimmersive Co.**, Encino, CA (US)
- (72) Inventors: **David Trought**, Richmond (AU); **Brody Payne**, Richmond (AU); **Rodney Brown**, Richmond (AU); **Andrew Castro**, Los Angeles, CA (US); **Stephen Bradford**, Los Angeles, CA (US); **Robert Reich**, Los Angeles, CA (US); **Tyler Garland**, Los Angeles, CA (US); **Aldis Rauda**, Los Angeles, CA (US); **Michael Latham**, Los Angeles, CA (US); **Pongnut Krainichakul**, Los Angeles, CA (US); **Ji Hyun Kim**, Los Angeles, CA (US); **Kira Song**, Los Angeles, CA (US); **Charlie Melvoin**, Encino, CA (US); **Sheera Goren**, Encino, CA (US)
- (73) Assignee: **Swimmersive Co.**, Encino, CA (US)
- (**) Term: **15 Years**
- (21) Appl. No.: **29/673,062**
- (22) Filed: **Dec. 11, 2018**

CLAIM

The ornamental design for a wireless audio headset, as shown and described.

DESCRIPTION

FIG. 1 is a bottom plan view of a wireless audio headset.

FIG. 2 is a top plan view.

FIG. 3 is a front elevation view.

FIG. 4 is a rear elevation view.

FIG. 5 is left side elevation view.

FIG. 6 is a right side elevation view; and,

FIG. 7 is a perspective view.

The broken lines immediately adjacent the shaded surfaces represent the bounds of the claimed design while all other broken lines are directed to environment that are for illustrative purposes only; the broken lines form no part of the claimed design.

1 Claim, 7 Drawing Sheets
